Primary Examiner — Selina Sikder*(74) Attorney, Agent, or Firm* — Studebaker & Brackett PC(57) **CLAIM**

The ornamental design for a light source module, as shown and described.

DESCRIPTION

FIG. 1 is a front perspective view of the front, right, and bottom sides of a light source module showing a first embodiment of our new design;

FIG. 2 is a front view thereof;

FIG. 3 is an enlarged view at a part 3 shown in FIG. 1; FIG. 4 is an enlarged view at a part 4 shown in FIG. 2; FIG. 5 is an enlarged end view at a cut part 5 shown in FIG. 4, with omitting the interior mechanism.

FIG. 6 is a front perspective view of the front, right, and bottom sides of a light source module showing a second embodiment of our new design; and

FIG. 7 is a front view thereof;

FIG. 8 is an enlarged view at a part 8 shown in FIG. 6; FIG. 9 is an enlarged view at a part 9 shown in FIG. 7; and, FIG. 10 is an enlarged end view at a cut part 10 shown in FIG. 9, with omitting the interior mechanism.

The broken lines shown represent unclaimed subject matter of the light source module and form no part of the claimed design. The dash-dot lines represent the boundary the claimed design and unclaimed design.
